US00D549905S

(12) **United States Design Patent** (10) **Patent No.:** **US D549,905 S**
Bobrosky et al. (45) **Date of Patent:** **** Aug. 28, 2007**

(54) **HANDLE FOR A VACUUM CLEANER**

(75) Inventors: **Vincent Bobrosky**, Normal, IL (US);
Randall Sandlin, Bloomington, IL (US); **Jeffrey Smith**, Bloomington, IL (US)

(73) Assignee: **Electrolux Homecare Products, Ltd.**, Cleveland, OH (US)

(**) Term: **14 Years**

(21) Appl. No.: **29/264,785**

(22) Filed: **Aug. 18, 2006**

(51) **LOC (8) Cl.** **15-05**

(52) **U.S. Cl.** **D32/34**

(58) **Field of Classification Search** ..... D32/21-23, D32/31, 15-16, 30; 15/320, 327.1, 327.2, 15/327.6, 327.7, 328-329, 331, 344, 350-353, 15/361, 410-411, DIG. 10; 55/DIG. 3, 337, 55/345, 429, 447; 95/271; 210/512.1; 16/429, 16/114.1, DIG. 19, 419; D8/307-308

(57) **CLAIM**

We claim the ornamental design for a handle for a vacuum cleaner, as shown and described.

DESCRIPTION

FIG. 1 is a rear isometric view of a handle for a vacuum cleaner showing the claimed design;

FIG. 2 is a front isometric view of the handle for a vacuum cleaner;

FIG. 3 is a rear view of the handle for a vacuum cleaner;

FIG. 4 is a bottom view of the handle for a vacuum cleaner;

FIG. 5 is a front view of the handle for a vacuum cleaner;

FIG. 6 is a left view of the handle for a vacuum cleaner;

FIG. 7 is a right view of the handle for a vacuum cleaner; and,

FIG. 8 is a top view of the handle for a vacuum cleaner.

The details shown in broken lines form no part of the claimed design.

1 Claim, 8 Drawing Sheets
